UNITED STATES PATENT OFFICE.

ROBERT H. McDONOUGH, OF DETROIT, MICHIGAN.

COMBINATION-LOCK.

1,271,739.

Specification of Letters Patent.

Patented July 9, 1918.

Application filed September 1, 1917. Serial No. 189,276.

To all whom it may concern:

Be it known that I, ROBERT H. McDONOUGH, a citizen of the United States of America, residing at Detroit, in the county 5 of Wayne and State of Michigan, have invented certain new and useful Improvements in Combination-Locks, of which the following is a specification, reference being had therein to the accompanying drawings.

10 The invention relates to combination locks for automobiles and its object is to provide a combination lock particularly adapted to be associated with a valve controlling the liquid fuel supply to the motor of the vehicle 15 and with switches controlling the ignition and light circuit to lock said valve in closed position and said switches open, and thereby prevent starting of the motor of the vehicle by unauthorized persons.

20 In the drawings:

Figure 1 is a front view of the casing of the combination lock;

Fig. 2 is a rear view of said casing;

25 Fig. 3 is a view similar to Fig. 2 but with the rear cover-plate removed so as to disclose the interior mechanism, the parts being shown in locked position;

Fig. 4 is a view similar to Fig. 3 but showing the parts in unlocked position;

30 Fig. 5 is a sectional view taken on line 5-5 of Fig. 3, the casing being shown mounted upon the dash, and the controlled valve and switches shown;

Fig. 6 is a front view of the casing with 35 the dial removed and the parts shown in locked position;

Fig. 7 is a view similar to Fig. 6 but showing the parts in unlocked position;

Fig. 8 is a front view of the dash with the 40 casing removed, showing a plate which covers certain mechanism carried by the dash, to which plate the casing is adapted to be secured;

Fig. 9 is a view similar to Fig. 8 but with 45 said plate removed so as to uncover the mechanism carried by the dash;

Fig. 10 is a rear view of the dial;

Fig. 11 is a perspective detail view of two 50 cams showing interchangeable faces thereof adapted to drive one from the other with lost motion.

In these views the reference character 1 designates the dash of a motor vehicle and 2 a valve in front of said dash controlling the flow of liquid fuel through a pipe 3 and 55 thence to the motor (not shown). The stem 4 of said valve projects rearwardly through the dash and into a recess 5 formed in the rear face thereof. Within said recess a locking pin 6 is passed transversely through the 60 stem to restrain the same against forward displacement. Within said recess, at each side of the stem 4, there are also respectively located switches for controlling the light and ignition circuit, each of said switches 65 comprising an actuating stem 7 having a portion journaled in the dash, a contact arm 8 mounted upon the stem but insulated therefrom and one or more fixed contact members 9 adapted to be engaged by the 70 arm 8 in a certain rotative position of the stem 7. The ends of the stems 4 and 7 are transversely slotted as indicated at 10 to adapt them for engagement with other parts hereinafter described. To the rear of the 75 dash there is attached a circular cover-plate 11 which overlies the recess 5 and through which the stems 7 slightly project, (see Fig. 8). At the center said plate is formed with an opening 12 to allow engagement with the 80 valve stem 4 of actuating means therefor carried by the casing.

The casing 13 is of cylindrical form and is provided with an annular flange 14 adapted to bear upon the dash and to be attached 85 thereto. Adjacent its front said casing is integrally formed with a transverse partition 15 producing front and back compartments 16 and 17 respectively, the latter of which is considerably the larger. The compartment 17 is closed normally by a plate 18 secured by screws 19 to lugs 20 formed internally of the casing at opposite sides thereof. A sleeve comprising parts 21, 22 and 23 is mounted centrally of the casing. 90 The part 23 rotatively engages in a central aperture in the partition 15 and projects slightly into the chamber 16. The part 22, within the chamber 17, abuts against the partition 15, and the part 21, which is of 100 relatively smaller diameter, extends through the chamber 17. Through said sleeve there

is passed a screw 24 having its head bearing against the rear end of the sleeve and its front end threaded into a boss 25 formed centrally upon the rear surface of a dial 5 member 26 which constitutes a closure for the chamber 16. Said dial has a beveled periphery with radial markings which, in the operation of unlocking, are to be registered with a radial mark 27 on the casing 10 in the usual manner.

Within the compartment 16 a locking member 28 is journaled upon the sleeve part 23, said member being formed with lugs 29 and 30 which, as is well shown in Figs. 6 and 15 7, are adapted respectively to have interlocking engagement with disk-shaped controlling elements 31 and 32 having stems 33 journaled in the partition 15, and projecting through orifices 34 in the cover-plate 18 for engagement 20 with the stems 7. As shown, the controlling member 31 for the lights has three locking positions corresponding respectively to open and closed positions of the switch controlling the light circuit and to a position in 25 which the lights are dimmed, and the member 32 controlling the ignition circuit has two locking positions respectively corresponding to the open and closed positions of the switch controlling the ignition circuit.

30 There is also mounted in the chamber 16 a disk-shaped member 35 for actuating the locking member, the same being carried upon one end of a pintle 36 which is journaled in the partition 15 and in the plate 35 18. Each of the members 31, 32 and 35 projects peripherally through a corresponding slot in the side of the casing and has a handle or knob 37 exterior to the casing to facilitate manipulation. Each of said three 40 members is peripherally marked with words such as "Off" or "On" or "Open", which words according as they are exposed exteriorly of the casing indicate the condition of the controlled circuit or mechanism.

45 Control is transmitted from the actuating member 35 to the locking member 28 through a lever 40 journaled within the chamber 17 upon the part 22 of the sleeve, one extremity of said lever being slotted for engagement with a pin 41 carried by said actuating member and projecting through an arcuate slot 42 in the partition 15, and the other end of said lever carrying within the chamber 17 a post 43 from which a reduced 50 portion 44 projects through an arcuate slot 43a in the partition 15 for engagement with the locking member. The post 43 forms a pivotal support for a plurality of pawls 44a, the three being employed in this instance. The 55 free ends of said pawls are formed with arcuate recesses which are adapted in one position of the pawls to partially embrace a pin 45 passing through the plate 18 and threaded into the partition 15. When said 60 pawls are thus engaged with the locking pin

45, the lever 40 occupies the position disclosed in Fig. 3, being restrained by said pawls against displacement from said position, and the locking member 28 has engagement with the controlling members 31 and 32 70 so as to retain the same in one of the positions disclosed in Figs. 6 and 7. Thus it is seen that the pin 45 is adapted to form an abutment for the pawls whereby the various parts are held in locked position. In order 75 that the pawls may automatically engage the locking pin 45 as soon as the lever 40 is displaced to the position shown in Fig. 3, each of said pawls has attached thereto a spring 80 46, bearing at its free end upon a peripheral wall of the casing. For each pawl there is a corresponding cam 47 mounted upon the sleeve part 21, each cam being formed with a peripheral pointed tooth 48 for engagement 85 with a similarly shaped tooth upon the corresponding pawl to lift the pawl from engagement with the locking pin 45. The several cams are connected to each other by a lost-motion engagement established by any well-known means, as for example, by forming interengageable segments upon adjacent 90 cams; thus the cams may be successively operated to disengage their corresponding pawls by an oscillatory adjustment of a common actuating member, namely, the dial 26. 95 The driving cam of the series is that which is nearest adjacent the partition 15, said cam being keyed to the dial by a pin 50 passing eccentrically through the sleeve part 22 and engaging in one of a series of apertures 51 formed in the back face of the dial. Accidental rotation of the cams is prevented by spanners 52 which respectively engage 100 cylindrical hubs 53 formed on the cams and which are anchored by engagement with one 105 of the stems 33. Adjacent the pivot post 43 there is also mounted upon the lever 40 a post 54 which acts as a stop to prevent the pawls from bearing upon the peripheral 110 faces of the corresponding cams when disengaged from the locking pin 45. The cam 47 which is nearest adjacent the cover-plate 18 is notched to form a shoulder 55 and a pin 56 carried by the pintle 36 is adapted to engage said shoulder when the actuating 115 member 35 is rocked to accomplish unlocking of the mechanism. The cover-plate 18 has centrally journaled therein a sleeve 57, which sleeve rigidly carries an arm 58 within the chamber 17, the outer end of which arm pivotally engages the post 43, so as to cause said sleeve to undergo a slight rotation when the lever 40 carrying said post is rocked. Said sleeve projects through the 120 central opening 12 of the plate 11 when the casing is mounted upon the dash and is adapted to communicate its rotation to the stem 4 by the provision of a pin 59 mounted transversely in said sleeve engaging in the slot 10 in the said stem 4. The extremities 125 130

of the pin 59 project at each side of the sleeve 57 and a pair of opposed slots 60 are formed in communication with the opening 12 to allow the pin 59 to be passed through 5 the plate 11 and into the recess 5. As the parts within the casing are shifted to locking position the sleeve 57 is so rotated as to shift the pin 59 out of registration with the slots 60 and it thus becomes impossible to re- 10 move the casing from the dash until the dial has been manipulated according to a known combination so as to permit the mechanism to be shifted to unlocking position.

It is to be noted that the members 31 and 15 32 may be freely rocked to establish any desired control of the ignition and light circuits when the locking member 28 is shifted from engagement with said members. It is also to be observed that manipulation of 20 the member 35 serves not only to shift the member 28 to or from its locking position, but also throws the liquid supply valve 2 open or closed according as said locking member 28 is in operative or inoperative position. By the provision of a plurality of 25 apertures 51 in the rear face of the dial it becomes possible for a user of the lock to readily change the combination, this sometimes being desirable to prevent use of a 30 car by a person to whom the old combination is known. After having removed the casing from the dash and loosened the screw 24, the dial may be taken off and the pin 50 may be engaged in a different one of the 35 apertures 51. By causing the pin 56 to engage and slightly rotate one of the cams 47 while the mechanism is being unlocked, said cam is shifted from its pawl-raising position so that a proper manipulation of the dial 40 will be necessary to again raise the pawls after the parts have been readjusted to locking position.

What I claim as my invention is:

1. The combination with a pivotal member, of an abutment, a plurality of pawls engageable with said abutment in a certain position of the pivotal member for locking said member in said position, a plurality of cams respectively associated with said pawls, 50 each being adapted to lift its corresponding pawl out of engagement with said abutment, lost-motion connections between said cams, and means for adjusting said cams rotatively according to a predetermined combination to disengage all of the pawls from said abutment.

2. The combination with a pivotal member, of an abutment, a plurality of pawls engageable with said abutment in a certain position of the pivotal member for locking said member in said position, a plurality of cams respectively associated with said pawls, each being adapted to lift its corresponding pawl out of engagement with said abutment, lost-motion connections between said cams,

means for adjusting said cams rotatively according to a predetermined combination to disengage all of the pawls from said abutment, and a stop engageable by said pawls when the latter are disengaged from said abutment, limiting motion of the pawls toward the corresponding cams.

3. The combination with a locking member and means for actuating the same, of an abutment and a series of pawls respectively engageable with said abutment to prevent retraction of the locking member, a series of concealed cams for respectively actuating said pawls to release the locking member, lost-motion connecting means between said cams by which they may be successively actuated according to a predetermined combination to disengage all of said pawls from the abutment, and a stop engageable by said pawls when the latter are disengaged from said abutment, limiting motion of the pawls toward the corresponding cams.

4. The combination with a pivotal member, of an abutment, a plurality of pawls engageable with said abutment in a certain position of the pivotal member for locking said member in said position, a plurality of cams respectively associated with said pawls, each being adapted to lift its corresponding pawl out of engagement with said abutment, lost-motion connections between said cams, means for adjusting said cams rotatively according to a predetermined combination to disengage all of the pawls from said abutment, and means for automatically throwing the combination upon displacement of said pivotal member from its locking position.

5. The combination with a locking member, of an actuating member therefor and an intermediately pivoted lever transmitting control from the actuating member to the locking member, an abutment and a plurality of pawls engageable with said abutment in the position of the lever corresponding to the locking position of the locking member to restrain said lever and locking member from displacement, a plurality of cams connected by a lost-motion engagement and respectively associated with said pawls to individually disengage the same from said abutment, and means for adjusting said cams rotatively according to a predetermined combination to disengage all of the pawls from said abutment.

6. The combination with a pivotal member, of a plurality of pawls mounted upon said member, an abutment engageable by said pawls in a certain position of the pivotal member for locking said member in said position, a plurality of cams respectively associated with said pawls, each being adapted to lift its corresponding pawl out of engagement with said abutment, lost-

motion connections between said cams, and means for adjusting said cams rotatively according to a predetermined combination to disengage all of the pawls from said abutment.

7. The combination with a pivotal member, of a plurality of pawls mounted upon said member, an abutment engageable by said pawls in a certain position of the pivotal member for locking said member in said position, a plurality of cams respectively associated with said pawls, each being adapted to lift its corresponding pawl out of engagement with said abutment, lost-motion connections between said cams, and means for adjusting said cams rotatively according to a predetermined combination to disengage all of the pawls from said abutment, and a stop carried by said pivotal member engageable by said pawls when the latter are disengaged from said abutment, limiting motion of the pawls toward the corresponding cams.

8. The combination with a pivotal member, of a plurality of pawls mounted upon said member, an abutment engageable by said pawls in a certain position of the pivotal member for locking said member in said position, a plurality of cams respectively associated with said pawls, each being adapted to lift its corresponding pawl out of engagement with said abutment, lost-motion connections between said cams, means for adjusting said cams rotatively according to a predetermined combination to disengage all of the pawls from said abutment, and means for automatically throwing the combination upon displacement of said pivotal member from its locking position.

40 9. The combination with a locking member, of an actuating member therefor, an intermediately pivoted lever transmitting control from the actuating member to the locking member, a plurality of pawls pivoted upon said lever, an abutment engageable by said pawls in the position of the lever corresponding to the locking position of the locking member to restrain said lever and locking member from displacement, a plurality of cams connected by a lost-motion engagement and respectively associated with said pawls to individually disengage the same from said abutment, and means for adjusting said cams rotatively according to a predetermined combination to disengage all of the pawls from said abutment.

10. The combination with a pivotal member, of a plurality of pawls and an abutment engageable by said pawls in a certain position of the pivotal member to lock said member in said position, a plurality of cams mounted coaxially with the pivoted member and respectively associated with said pawls, each being adapted to lift its corresponding pawl out of engagement with said abutment,

means for adjusting said cams rotatively according to a predetermined combination to disengage all of the pawls from said abutment, a second pivotal member mounted coaxially with said first-named pivotal member, an arm rigidly projecting from the second pivotal member, and means pivotally engaging the outer portions of said arm and the first-named pivotal member whereby the two said pivotal members are actuatable in common.

11. The combination with a casing having a partition therein, of a rotative member journaled in said partition, a lever journaled upon said member at one side of the partition, a plurality of pawls mounted upon said lever, an abutment engageable by said pawls in one position of the lever to lock the lever in said position, a plurality of cams mounted upon said rotative member and respectively associated with said pawls, each being adapted to lift its corresponding pawl out of engagement with said abutment, lost-motion connections between said cams, a locking member at the other side of said partition having an engagement with said lever to restrain it from displacement when the lever is locked by said pawls, and an actuating member for the cams overlying said locking member.

12. The combination with controlled mechanism mounted upon a support, of a plate secured to said support and overlying said mechanism, control means for said mechanism, a casing carrying said control means, a member carried by the casing engageable with said plate to retain the casing upon the plate, and a common means for locking the last-named member against disengagement from the plate and for locking the control member in a fixed position.

13. The combination with controlled mechanism mounted upon a support, of a valve stem adjacent said mechanism, a plate secured to said support and overlying said mechanism and valve stem, control means for said mechanism, a casing carrying said control means, a member carried by the casing engageable with said plate to retain the casing upon the plate and detachably engageable with said valve stem for actuating the same, and means carried by the casing for locking the last-named member to prevent actuation of the valve stem and hold the casing in engagement with said plate and for locking said control means against actuation.

14. The combination with mechanism mounted upon a support, of a control stem for said mechanism detachably engageable therewith, a casing carrying said control stem and detachably engageable with said support, means for locking said control stem carried by the casing, and actuating members within the casing for said stem and said

locking means respectively, said members projecting exteriorly of the casing and carrying indicia adapted to be exposed upon the projecting portions of said members.

5 15. The combination with a pivotal member, of actuating means therefor, a pawl mounted upon said pivotal member and an

abutment engageable by said pawl in a certain position of the pivotal member to lock the lever in said position, said pawl having a bearing upon said abutment during movement of the pivotal member.

In testimony whereof I affix my signature.

ROBERT H. McDONOUGH.
